UNITED STATES PATENT OFFICE.

EUGENE GASSMANN, OF BROOKLYN, NEW YORK, ASSIGNOR TO EISEMANN MAGNETO CO., OF BROOKLYN, NEW YORK, A CORPORATION OF NEW YORK.

IMPULSE-STARTER.

1,251,216.

Specification of Letters Patent. Patented Dec. 25, 1917.

Application filed January 26, 1917. Serial No. 144,647.

To all whom it may concern:

Be it known that I, EUGENE GASSMANN, a citizen of Germany, and a resident of the borough of Brooklyn, county of Kings, and 5 State of New York, have invented certain new and useful Improvements in Impulse-Starters, of which the following is a complete specification.

My invention relates to electrical ignition 10 devices for internal combustion engines, and consists in the devising of mechanism, adapted to be connected to an electrical current generator, and whereby the armature, or other rotatable part of the electric current 15 generator, may be driven, independently of the means provided for driving the generator from the shaft of the engine, through a part of its revolution at a sufficient speed to produce a spark of ample capacity to ignite 20 the charge in the cylinder of the engine. When the engine is running, the mechanism serves as a coupling, connecting the drive shaft with the armature shaft, or other rotating part of the electric current generator. 25 An impulse starting mechanism, constructed according to my invention, is illustrated in the accompanying drawings, wherein—

Figure 1 is a perspective view of the 30 driven member of the impulse starting mechanism, part of the rim being broken off to disclose its interior construction;

Fig. 2 is a similar view of the driving member;

Fig. 3 is a plan view of the yoke or coupling member;

Fig. 4 is a plan view of the driven member with the coupling member, the spring, yieldingly connecting the driving and the 40 driven member, and (in section) parts of the driving member; the enumerated parts of the mechanism being shown in their relative positions when the magneto is driven by the engine, the impulse starting mechanism 45 then acting as a coupling;

Fig. 5 is a longitudinal sectional view of the impulse starting mechanism assembled; the parts being shown in their relative positions when the generator is not running;

Fig. 6 is a cross-sectional view on line 6—6 indicated in Fig. 5; the parts being shown in the same position as in Fig. 5;

Fig. 7 is a cross-sectional view like Fig. 6, but showing the parts in their relative positions when the driven member is held fast

by the engagement of the coupling member in the notch of the catch-plate, located underneath, and the driving member rotated in advance of the driven member to the point at which its cam-part begins to lift 60 the coupling member from its engagement with the catch-plate;

Fig. 8 is a fragmental side elevation, and

Fig. 9 a front view, of a magneto with the impulse starting mechanism applied to the 65 armature shaft.

Figs. 10 and 11 are sectional views like Figs. 6 and 7 respectively, but showing a modified construction of my improved impulse starter, wherein a flat coiled spring is 70 used in place of the spirally wound spring, employed in the preferred embodiment of my invention; Fig. 10 shows the parts in their relative positions when the magneto is driven by the engine, the impulse starting 75 mechanism then acting as a coupling, and Fig. 11 shows the parts in their relative positions when the driven member is held fast by the engagement of the coupling member with the notch in the catch-plate, located underneath, and the driving member rotated, in advance of the driven member, to the point at which its cam-part begins to lift the coupling member from its engagement with 80 the notch in the catch-plate.

85

The driven member of the impulse starter (see Fig. 1) designated 11 in the drawings, is made in the form of a cylindrical casing, centrally perforated and provided with a hub 12, which is interiorly fitted upon the 90 shaft of the rotatable part of an electric current generator, and is provided with a key way 13 for fixing it thereto. The rim 14 of this driven member is made of sufficient width to accommodate the parts of the impulse starting mechanism housed therein. The driving member 15 (see Fig. 2) is made in the form of a disk, also centrally perforated and provided with a hub 16, which is interiorly fitted upon the hub 12 of the 100 driven member. The hub 16 of the driving member is recessed as shown in Fig. 2, to form the cam, divided by the notch 19 into the two parts 17 and 18, co-acting with the cams 24 and 25 of the yoke or coupling member 21 (see Fig. 3) as explained farther on. This member is formed as an elliptical disk with a bolt-like extension 22, which I designate the "trigger", on one end, extending in line with its long axis, and one or two 110

segments 23, affixed thereto on the other end. The trigger 22 engages in the aperture 26 made in the rim 14 of the driven part 11 of the device, the trigger 22 being shaped to slide freely therein. The dimensions of the yoke 21, and of the trigger 22, are so proportioned, that the trigger is always in engagement with the aperture 26 in the rim 14 of the driven member (see Fig. 4) whereby 5 the two members are constantly locked together. The segment, or segments, 23 act as a weight to cause the yoke 21 to be reciprocated, *i. e.* drawn in, by centrifugal force, into the driven member when the device is 10 rotated, and to be moved by gravity in the opposite direction when the electric current generator stands still. The above mentioned cams, designated respectively 24 and 25, are formed on the interior surface of the yoke, 15 approximately opposite each other. These two cams are shaped to co-act with the above mentioned cam-parts 17 and 18, and with the notch 19, formed on the hub of the driving member, in the operation of the impulse 20 starting device. They are so located, and so dimensioned, that one of them always projects into the circumference of the hub 16 of the driving part 15, that is to say, when the yoke 21 is at the limit of its inward motion, withdrawn within the outer circumference in the rim 14 as shown in Fig. 4, the cam 25 projects into the circumference of the hub 16, whereas when the yoke 21 is in its 25 opposite extreme position, the cam 24 is withdrawn within the circumference of the hub 16, as shown in Figs. 5, 6 and 7. When the parts are in the position shown in Fig. 4, the cam 25 engages in the notch 19, made in the hub 16 of the driving member, thus clutching the driven 30 and the driving member together.

The driven member 11 and the driving member 15 are yieldingly connected by the spring 27. This may be a spiral spring between the block 28, secured to the rim 14 of the driven member 11, and the block 29 secured to the driving member 15, one of its ends connecting with the block 28 and the other with the block 29, as shown in the drawings, or a flat spring coiled in the same 35 space and having one end secured to the hub 16 of the driving member 15, and the other end to the rim of the driven member 11, may be used instead. This construction is illustrated in Figs. 10 and 11, which are 40 sectional views like those shown in Figs. 6 and 7, but in Fig. 10 the component parts of the modified construction of my improved impulse starter are shown in the same relative positions as shown in Fig. 4, that is, when the impulse starter acts as a coupling, the magneto being driven by the engine. In Fig. 11 the relative positions of these parts are the same as shown in Fig. 7, when the driven member is held by the engagement of 45 the coupling member in the notch in the

catch-plate, and the driving member advanced, relatively to the driven member, to the point, at which its cam-part begins to lift the coupling member from the notch.

Referring to Fig. 10, the part designated 50 11 is the same driven member as hereinbefore described, and to it is secured, by rivets 40, or otherwise, the segmental piece 38; the segmental piece 39 is secured to the driving member 15. These segmental pieces correspond in their purpose and function to the blocks 28 and 29 of the hereinbefore described preferred form of embodiment of my invention. The segmental piece 38 is shaped to afford hooking thereto, as shown at 37, of one end of the coiled band spring 27; the other end of the spring 27 is secured in the slot, made in the cam-part 16 of the driving member 15, as shown at 42. In all other respects the modified construction of my improved impulse starter is the same as shown in the other figures of the drawing, and as hereinbefore described. In both constructions the spring yieldingly holds the driven and the driving member in their relative positions, permitting of a partial rotation of the driving member 15 relatively to the driven member 11, and is set at tension when the driving member 15 is thus rotated in advance of the driven member 11. The web 55 33 (see Figs. 1 and 5) shown to be affixed to the rim 14 of the driven member, is used to avoid contact between the yoke 21 and the spring 27, which might, owing to the arch 23, protruding from the plane of the yoke 21, interfere with the operation of the said spring. It serves also to guide the reciprocatory movements of the yoke or coupling member 21. 60

The relative positions of the driven and the driving member, and of the other parts of my improved impulse starter, shown in Fig. 4, are the positions in which they are maintained while the engine is running, the centrifugal force, acting on the weighted parts 23 of the yoke or coupling member 21, maintaining the engagement of its cam-point 25 in the notch 19 of the driving member 15, and holding the parts in that position. When, however, the engine stops, the 65 centrifugal force ceases to act and the yoke or coupling member 21 drops when the impulse starter is brought into the position shown in Figs. 5, 6 and 7. Thereby its cam-point 25 is disengaged from the notch 19 in the hub 16 of the driving member 15, and the driven member 11, and the driving member 15, are held in their relative position solely by the spring 27. The driving member 15 may then be rotated in advance of the 70 driven member 11. To enable this to be done against the resistance of the spring 27, the catch-plate 30, secured to the frame of the electric current generator (see Figs. 7, 8 and 9) by the stud bolts 32, is provided. 75

The trigger 22 engages in the notch 31 of the catch-plate 30, when the yoke or coupling member 21 drops by gravity as above explained, and the driven member 11 is thereby held against rotating with the driving member 15, and the spring 27 is compressed (or would be wound up, if a coiled spring were used instead) and thus set at tension. When the cam-part 17 on the hub 16 is brought into co-action with the cam 24 on the yoke, or coupling member 21, the further continued rotating of the driving member 15, which is then in the position shown in Fig. 7, results in withdrawing the trigger 22 from the notch 31, thereby releasing the driven member 11. Then the spring 27, re-acting against the block 28, propels the driven member 11, and the rotary part of the electric current generator to which the driven member 11 is secured, at a comparatively high speed through an arc of its revolution. This results in producing the requisite current for a spark of sufficient volume and intensity to ignite the charge in the cylinder and thereby to start the engine running. By this partial revolution also the cam-point 25 of the yoke or coupling member 21 is brought in alinement with the notch 19 of the driving member 15. The electric current generator is driven by a gear, or a chain and sprocket wheel transmission, from the engine shaft. For this a bushing 34 (see Fig. 8) is fixed in the hub 16 of the driving member 15, so that a gear or a sprocket wheel may be secured thereto. After the engine is started, the rotating of the impulse starter produces the requisite centrifugal force to retract the yoke or coupling member 21, whereby the cam-point 25 is brought into engagement with the notch 19. The driving and the driven member are thus coupled together, and any deviation in the timing of the apparatus is precluded. The parts of the impulse starter are then in the positions illustrated in Fig. 4, the spring 27 being inactive and not subjected to any stress whatever.

I claim as my invention:

1. An impulse starter for an electrical current generator, comprising a driven member, adapted to be secured to the rotatable part of the generator; a driving member rotatably mounted on the driven member; a reciprocating yoke between the driven and the driving member, the yoke having a bolt-like extension permanently engaging with the driven member and projecting beyond the periphery thereof when the yoke is reciprocated to the end of its motion in that direction; means for engaging the bolt-like extension when thus projected beyond the periphery of the driven member; a spring; means on the driven and on the driving member for setting it at tension by rotating the driving member in advance of

the driven member, and coöperating means on the yoke, and on the driven member, for moving the yoke to recede its bolt-like extension to release the driven member, after the spring is set at tension; substantially as herein shown and described. 70

2. An impulse starter for an electrical current generator, comprising a driven member having a hub adapted to secure it to the rotatable part of the generator; a driving member rotatably mounted on the hub of the driven member; a cam, having a recess on the hub of the driving member; a yoke adapted to be reciprocated on the driven member and having a bolt-shaped projection engaging in a correspondingly shaped aperture in the rim of the driven member; means for engaging the bolt-shaped projection of the yoke when projected beyond the periphery of the driven member, and thereby holding the latter against rotation; a spring yieldingly connecting the driving and the driven members; means for setting the spring at tension by rotating the driving member in advance of the driven member; cams on the yoke in position to coöperate with the cam on the hub of the driving member to recede the bolt-shaped projection from its engagement with the holding means when the driving member is rotated in advance of the driven member; substantially as herein shown and described. 85

3. An impulse starter for an electrical current generator, comprising a driven member adapted to be secured to the rotatable part of the generator; a driving member rotatably mounted on the driven member; a yoke between the driven and the driving member, adapted to be reciprocated alternately by gravity and by centrifugal force; a bolt-like extension on the yoke permanently engaging with the driven member and projecting beyond the periphery thereof when the yoke is moved by gravity; means for engaging the bolt-like extension when thus projected; a spring yieldingly connecting the driven and the driving member and adapted to be set at tension by rotating the driving member in advance of the driven member; and means on the yoke, and on the driving member, adapted to coöperate to raise the yoke and thereby to recede its bolt-like extension within the periphery of the driven member when the driving member is rotated in advance of the driven member; substantially as herein shown and described. 110

4. An impulse starter for an electrical current generator, comprising a cylindrical casing adapted to be secured to the rotatable part of the generator; a coupling member rotatable relatively thereto; a radially oscillating yoke revolving with the casing and engaging positively with the coupling mem- 125
130

- ber when at the limit of the motion of the yoke caused by centrifugal force; a stop engaging the yoke and holding it, and the casing, against rotation when the yoke is at 5 the other limit of its motion; a spring yieldingly connecting the casing and the coupling member, and permitting relative rotation of them, and coöperating cams on the yoke, and on the coupling member, adapted to move 10 the yoke into a position intermediate the point of engagement of the casing and with the coupling when the spring is placed under stress by forward movement of the coupling relative to the casing; substantially as 15 herein shown and described.
5. An impulse starter for an electrical current generator, comprising a cylindrical casing adapted to be secured to the rotatable part of the generator; a coupling member 20 rotatable relatively thereto; a radially oscillating yoke, mounted in the casing and revolving therewith, and engaging positively with the coupling member when at the limit of the motion of the yoke caused by centrifugal force; a stop engaging the yoke and holding it, and the casing, against rotation when the casing and the yoke are at rest; a spring yieldingly connecting the casing and the coupling member; a cam-point on the 25 yoke, and a coöperating cam part on the coupling member, adapted to move the yoke to disengage it from the stop, and into an engagement with the coupling, when the spring is set at tension by rotating the coupling member forward relative to the casing; substantially as herein shown and described.
6. An impulse starter for an electrical current generator, comprising a cylindrical 30 casing adapted to be secured to the rotatable part of the generator; a yoke rotating with the casing, and radially reciprocating thereon when actuated alternately by centrifugal force and by gravity; a stop adapted to be 35 engaged by the yoke and thereby to arrest its rotation and the rotation of the casing when the yoke is at the lower limit of its motion; a finger on the yoke adapted to positively interlock with the coupling member 40 when the yoke is at the limit of its motion caused by the centrifugal force; a spring yieldingly connecting the casing and the coupling member, and permitting a limited forward movement of the coupling member 45 relative to the casing, and coöperating cam parts on the yoke, and on the coupling member, adapted to release the yoke, and the casing from the stop, when the coupling member is at the forward limit of its rotary motion relative to the casing; substantially as herein shown and described.
7. An impulse starter for an electrical

current generator, comprising a casing adapted to be secured to the rotatable part of the generator; a coupling member rotatable relative to the casing; a radially oscillating yoke revolving with the casing and engaging with the coupling member when the yoke is at the limit of its motion propelled by centrifugal force; a stop adapted 65 to intercept and lock the yoke, and the casing, and preventing it from rotating when the yoke is at the lower limit of its motion; cam members on the coupling member and on the yoke adapted to move the yoke into 70 a position releasing it, and the casing, from the stop, and a spring resisting rotary movement of the coupling member relative to the yoke to the cam releasing position, and then driving the casing forward; substantially as 75 herein shown and described.

8. The combination with a driven member, secured to the rotatable part of an electric current generator, a driving member rotatably mounted thereon, and a spring set 80 between so as to be tensioned by rotating the driving member in advance of the driven member, of a coupling device permanently engaging with the driven member and adapted to be brought automatically in engagement with the driving member when the driving member is rotated to a predetermined point in advance of the driven member, and means on the coupling device for holding it in engagement with the driving 85 member while the generator is driven at or above its normal speed; substantially as 90 herein shown and described.

9. The combination with a driven member, secured to the rotatable part of an electric current generator, a driving member rotatably mounted thereon, and a spring set 100 between so as to be tensioned by rotating the driving member in advance of the driven member; of a coupling device having a bolt-like extension permanently engaging with the driven member and projectable beyond the periphery of the driven member; retaining means for engaging the bolt-like extension when projected beyond the periphery 105 of the driven member; means on the said coupling device and on the driving member, whereby the coupling device is brought automatically in engagement with the driving member, and the bolt-like extension receded 110 from its engagement with the retaining means, when the driving member is rotated to a predetermined point in advance of the driven member; substantially as 115 herein shown and described.

EUGENE GASSMANN.
